CALCULATING MACHINE

George C. Chase, South Orange, N. J., assignor to
 Monroe Calculating Machine Company, Orange,
 N. J., a corporation of Delaware

Application January 17, 1934, Serial No. 706,950

5 Claims. (Cl. 235—79)

The invention has relation to calculating machines, and more particularly to means for effecting a single registration in the accumulating register of such a machine without changing the reading of the multiplier-quotient register there-
 5 of.

Calculating machines are commonly provided with multiplier-quotient registering mechanism which is in effect a revolution counter, and which 10 effects either an additive or a subtractive registration during each cycle of operation of a machine. Therefore, in operating a motor driven calculating machine, it has been customary, in transferring a dividend from the keyboard of the 15 machine to the main register (or other value which it is desired to register without disturbing the multiplier-quotient register) to effect an ordinary additive operation; clear the keyboard, and thereafter to remove the unwanted regis-
 20 tration from the multiplier-quotient register. This last operation is sometimes effected by a subtractive operation of the machine which, since the keyboard has been cleared, will make no change in the main register, but will reversely 25 operate the multiplier-quotient register, to remove the previous registration therefrom. This has entailed three manual operations, and according to the present invention it is proposed to effect such operations by mechanism responsive to the depression of a single operating key.

The invention consists in the novel construction and combination of parts, as set forth in the appended claims.

In the accompanying drawings, illustrating the 35 invention:

Fig. 1 is a right side elevation of a calculating machine embodying the invention, with the casing removed.

Fig. 2 is a left side elevation of the same, with 40 the casing removed.

Fig. 3 is a detail elevation of the dividend key and associated parts, these parts being shown in normal position.

Fig. 4 is a similar view, with the parts shown in 45 the position taken at the end of the additive cycle of operation, the dividend key being held depressed.

Fig. 5 is a detail elevation of the change lever for a modified form of quotient register, with 50 associated parts.

Fig. 6 is a similar view of the change gearing for the quotient register.

Fig. 7 is a detail elevation, taken at right angles to the plane of Figure 6.

55 The invention is shown as applied to a Monroe

calculating machine, including motor drive mechanism constructed in accordance with the disclosure of U. S. Patent 1,566,650, issued to George C. Chase on December 22, 1925.

In this machine, the depression of a plus bar 5 120, or of a minus bar 121 (Fig. 1) will rock a clutch lever 111 (Fig. 2) into engagement with one or another of the elements of the differential gear reversing transmission mechanism 105, this engagement serving through a suitable gear 10 train to effect forward or reverse movement of a counting finger 71 (Fig. 1), mounted on a shaft 73, and also of the usual differential actuator mechanism, (indicated at 5 in Fig. 2) which is settable from the keyboard 18 of the machine. 15 From the actuators 5 the forward or reverse movement is transmitted to the numeral wheels 13 of the main register.

The special motor key forming the subject of the present invention will for convenience be 20 termed a dividend key, although it is obvious that this key may be useful in entering other values into the wheels 13 of the machine.

The dividend key, numbered 87 on the drawings, is shown as mounted immediately inside the 25 right hand frame plate of the machine and is provided with a pawl 88 adapted in the depression of the key to rock a bell crank lever 89 from the position shown in Fig. 3 into the position shown in Fig. 4, this bell crank lever being held 30 in either of its two adjusted positions by a spring click 90. When the key 87 is fully depressed, a tail 91 of the pawl 88 will contact with a stud 92, moving the pawl out of engagement with the bell crank lever 89.

35 Bell crank lever 89 has an aperture loosely engaged by a pin mounted in one arm of a lever 93, fulcrumed upon the stud 92, the other arm of said lever being provided with a pivoted crosshead 94, held in relation to the lever by a spring 95 and 40 a stop 96. In the movement of lever 93 from the position of Fig. 3 to that shown in Fig. 4, cross-head 94 will drop away from engagement with a pin 97, bringing a lug 98 of said cross-head into 45 position above an arm 99 of rock shaft 125. Rock shaft 125 is the connecting member between the plus and minus bars 120, 121 and the setting lever 128 (shown in Fig. 2) which is provided with opposed shoulders adapted to contact with a pin 50 129 in the reversing clutch lever 111. Therefore, upon depression of key 87, cross-head 94, contacting with arm 99, will rock the shaft 125 in a counter-clockwise direction as seen in Figs. 2, 3, and 4, and will throw the clutch lever 111 into 55

additive clutch engagement with the gearing 105, starting an additive registration.

One of the gears 76 of the driving train (Fig. 1) is provided with a shaft 77 upon which is mounted, inside the right hand frame plate, a cam 100 (Figs. 3 and 4). The above-described movement of lever 93, has brought an upper lug 101 of cross-head 94 against the shoulder of cam 100, as shown in Fig. 4, and, shaft 77 rotating in a clockwise direction during the additive movement of the parts, cam 100 will move cross-head 94 out of contact with the arm 99 of shaft 125, whereupon said shaft, under the influence of a suitable spring on setting plate 128 will return to its normal po-

10 sition, illustrated in full lines in Figs. 3 and 4. At the end of the cycle of additive movement lug 101 will fall from the high point of cam 100 into the position shown in Fig. 4, the lug 98 now lying below arm 99.

20 As setting lever 128 was rocked back to normal position a lever 134 (Fig. 2) was allowed to move under the influence of its spring, carrying a pawl 136 into engagement with a trigger 31 and disengaging said trigger from a pawl 25, whereupon said pawl was allowed to drop into engagement with a rock lever 22 connected by a rod 21 and crank 20 with the shaft 73. Pawl 25, falling behind a shoulder of rock arm 22 serves to connect stop lever 24 with said rock lever so that the 25 two parts will move forwardly in unison, tensioning a spring 28 and also, through engagement of a cam arm 144 of lever 24 with a pin in reversing clutch lever 111, serving to restore said clutch lever to neutral or unclutching position. Thus, the 30 differential actuators and other driven parts are allowed to overrun their full cycle position, and are then returned to and through such position by the spring 28. As the parts pass reversely through full cycle position the cam 100, turning 35 counter-clockwise as seen in Fig. 4, will engage the lug 101 and lift cross-head 94 and lever 93 from the position shown in Fig. 4 to that shown in Fig. 3, the lug 98 of cross-head 94 moving the arm 99 of shaft 125 into the dotted line or subtract position shown in Fig. 4. This serves to throw the clutch yoke 111 into subtractive clutch position, and a subtractive cycle of operation results.

50 During the first or additive cycle of operation, however, a lug 102 of bell crank lever 89 has thrown a non-repeat lever 16 into active position wherein a cam portion of said lever is engaged by a rotary tooth 17. Therefore, after the amount 55 on keyboard 18 has been registered, tooth 17 will move lever 16 into engagement with a clearing lever 15, adapted to release the depressed keys of the keyboard 18 in well-known manner, as shown for instance in U. S. Patent 1,432,616, issued to E. E. Phinney on October 17, 1922. The 60 non-repeat lever 16 is also under the control of a key 34, which, when latched in depressed position allows lever 16 to stand inactive, but when unlatched and allowed to rise, operates a rocker 35 into contact with the lever 16, moving the latter into the path of movement of the tooth 17.

65 It will be obvious from the above-description, that upon the depression of dividend key 87 the machine will effect a single cycle of additive operation, registering the amount set on keyboard 70 18 in the wheels 13, registering 1 in a wheel 85, and clearing the keyboard 18. Thereupon the machine will be reversed and will effect a single 75 cycle of subtractive operation, during which there will be no registration on the wheels 13, but during which the registration of 1 will be sub-

tracted from the wheel 85, leaving said wheel at 0.

As soon as cross-head 94 was lifted by cam 100 into the position illustrated in Fig. 3, lug 98 was moved out of engagement with arm 99 of shaft 125, by contact of the cross-head with pin 97, so that shaft 125 was allowed to return into neutral position, lever 134 thereupon moving to bring pawl 136 again in contact with trigger 31, to trip the pawl 25 and allow it to fall into engagement with arm 22. Therefore, the clutch will be disengaged and, after the inertia of the parts has been absorbed, they will settle into full cycle position.

10 It will be observed that the desired program 15 will be effected irrespective of the length of time during which the key 87 is held depressed by the operator, since the pawl 88 will not prevent the return movement of bell crank lever 89, and if the key 87 is released after the return of said bell 20 crank lever, the pawl will ratchet over the engaging portion of the lever and return to the position shown in Fig. 3.

The multiplier-quotient register, shown in Fig. 1, is operated from a nineteen-tooth gear wheel, 25 the periphery of the wheels 85 being customarily provided with two series of figures reading in reverse directions, so that, starting from 0, the wheel will be advanced in one direction during multiplication to register a multiplier, and will be 30 advanced in the opposite direction during division to register a quotient, in the proper manner. Other machines, however, have been provided with multiplier-quotient registers, the wheels of 35 which are operated from ten-tooth gears, and the peripheries of such wheels having a single series of figures, reading from 0 to 9. This type of multiplier-quotient register is frequently supplied with tens carry mechanism between the register 40 wheels, as shown, for instance, in U. S. Patent 40 1,504,741, issued to George C. Chase on August 12, 1924. This type of multiplier-quotient register is provided with change gearing, controlled by a hand lever, which lever may be set into multiplication or into division position, according to 45 the operation to be performed. In machines equipped with counting mechanisms of this character, it may be desired that the dividend key should set the change lever into division position, so that a following division operation may be performed without manual setting of this change lever.

50 For this purpose the lever 93 may be connected, through the stud 92, with an arm 183 (Fig. 5), provided with a pawl 184 normally engaging the 55 end of a second pawl 185 pivoted upon change lever 399. Upon depression of dividend key 87, arm 183 will be rocked downwardly, bringing pawl 184 into position beneath pawl 185. Upon movement of lever 93 back to its normal position 60 by the operation of cam 100, pawl 184 will act to lift pawl 185 to bring a tooth 186 of the latter pawl into engagement with a pin 187 fixed in a gear 75 of the driving train. When pawl 185 is thus lifted, however, the parts have been moved 65 beyond full cycle position in a subtractive direction, so that pin 187 will not contact with tooth 186 until the end of the subtractive cycle of operation, at which time it will act to throw lever 399 from multiplying position illustrated in Fig. 70 5, rearwardly into division position. This will operate to rock a yoke 392 engaging a clutch 391 of the change gearing, shifting said clutch out of engagement with one set of gears and into engagement with the opposite set. These gears 393 75

(Figs. 6 and 7) are of conventional design, and serve to rotate the counting finger shaft 389 forwardly or reversely, to move the counting finger 401 through the gear teeth of the related counting wheel 388 in forward or in reverse direction.

5 I claim:

1. In a calculating machine having a register adapted for positive and negative sign accumulation and a coacting quotient register comprising reversely rotatable numeral wheels; the combination with keys settable to determine amounts to be registered upon the first-named register, means for releasing the set amount keys, motor driven cyclic means for effecting registrations upon both of said registers and for operating the key releasing means, and clutch and sign determining means settable to effect operation of said motor driven cyclic means and including gears adjustable to reverse the direction of rotation of 20 a quotient wheel, of a manually operable key, a device settable by said key to set the clutch and sign determining means to effect a cycle of registering operation of the cyclic means and thereby cause operation of the key releasing means, and 25 a member operable by the cyclic means to readjust the set device and thereby adjust the reverse gears and effect a second cycle of quotient register operation.

2. In a calculating machine having a register 30 adapted for positive and negative sign accumulation, and a coactive reversible quotient register; the combination with keys settable to determine amounts to be registered upon the first-named register, means for releasing the set amount keys, 35 motor driven cyclic means for effecting registrations upon both of said registers and for operating the key releasing means, and clutch and sign determining means settable to effect operation of said motor driven cyclic means, of a manually operable key, a control device settable by said key to set the clutch and sign determining means to effect a cycle of positive 40 registering operation of the cyclic means and thereby cause operation of the key releasing means, and a member operable by the cyclic means to readjust the set control device to reverse the sign determining means and effect a cycle of negative driven movement.

3. In a calculating machine having a reversible 50 register, a reversible quotient register, and coactive reversible actuators for said registers including differentially adjustable elements related to the first-named register; the combination with keys settable to differentially adjust said actuator elements, means including a member driven in time with the actuators to release the set amount keys, motor drive means for said actuators, and clutch and sign determining means settable to effect movement of said actuators, of 55 control means including a rotary tooth associ-

ated with said motor drive means, a manually operable key, and a device settable by said key to set the clutch and sign determining means to effect a cycle of forward movement of the actuators and an operation of the key releasing means, said device being adjustable by the rotary tooth to reset the clutch and sign determining means to reverse the movement of the actuators and effect a cycle of movement thereof.

4. In a calculating machine having a register 10 adapted for positive and negative sign accumulation and a coactive reversible quotient register; the combination with keys settable to determine amounts to be registered upon the first-named register, means for releasing the set amount keys, 15 settable repeat, non-repeat means controlling the releasing means, motor driven cyclic means for effecting registrations upon both of said registers and for operating the key releasing means, and clutch and sign determining means settable to 20 effect operation of said motor driven cyclic means, of a manually operable key, a control device settable by said key to set the clutch and sign determining means to effect a cycle of positive registration and thereby cause operation of 25 the key releasing means, irrespective of the setting of the repeat, non-repeat means, and a member operable by the cyclic means to readjust the set control device and thereby reverse the sign determining means and effect a cycle of 30 negative driven movement.

5. In a calculating machine having a dividend register adapted for positive and negative sign accumulation, and a coactive quotient register reversible upon change of sign in the accumulative movement of the dividend register; the combination with secondary reversing means for the quotient register adapted to control registration like or unlike the sign of the accumulative movement of the dividend register, keys settable to 35 determine amounts to be registered upon the dividend register, means for releasing the set amount keys, motor driven cyclic means for effecting registrations upon both of said registers and for operating the key releasing means, and 40 clutch and sign determining means settable to effect operation of said motor driven cyclic means, of a manually operable key, a control device settable by said key to set the clutch and sign determining means to effect a cycle of positive 45 registration and thereby cause operation of the key releasing means, and a member operable by the cyclic means to readjust the set control device and thereby reverse the sign determining means and effect a cycle of negative driven 50 movement, and a device positioned by the readjusted control device and operable by the cyclic means to move the secondary reversing means to unlike registering position.

GEORGE C. CHASE. 60
